COMBUSTOR FOR HIGH FLOW VELOCITIES

Boleslaw Szczeniowski, Montreal, Quebec, Canada

Application July 30, 1948, Serial No. 41,565
In Canada August 2, 1947

3 Claims. (Cl. 60—39.14)

1

My invention relates to a combustor which creates a homogeneous air-fuel mixture and enables this mixture to be burnt while flowing with considerable velocity through a relatively short duct, i. e., the invention enables one to use a limited combustion space. While a combustor of this type may of course be used in various ways, it has been found especially suitable for jet engines in which application the space available for the combustor is strictly limited and a weighty combustor is undesirable.

The velocity of combustion, i. e. the velocity of displacement of the flame front cannot be precisely defined before the physical and chemical conditions of combustion are specified. In a closed vessel in which the mixture is ignited at a certain point, the flame is propagated in all directions, starting from this point, and at a certain moment the whole volume of the vessel is divided into two parts by the flame front: one burnt and the other not yet burnt. The velocity of flame propagation is variable here and depends not only on the initial conditions, i. e. on the pressure and temperature of the unburnt mixture, its chemical composition and its degree of homogeneity, but also on the fact that the part already burnt increases the velocity of the flame propagation in expanding, this expansion being due to the rise in temperature; thus the part not yet burnt is at the same time being compressed. Thus, an additional displacement of the flame front takes place, while the pressure in both parts, burnt and unburnt, increases, this latter fact changing the physico-chemical conditions influencing the velocity of flame propagation. The form of vessel also influences the process, as the rate of heat release is proportional to the volume burnt per unit of time, the combustion being assumed to propagate equally in all directions, thus resulting in a flame front of spherical form, which condition will only actually occur if the gas is at rest and is perfectly homogeneous.

In order to eliminate all influences except the initial physico-chemical conditions, an abstractive definition of the velocity of flame propagation is formulated as follows: a long tube of constant cross-section, insulated thermally from surroundings, open at one end and closed at the other, is filled with perfectly homogeneous air-fuel mixture. This mixture is ignited at the open end of the tube, simultaneously all over the cross-section. The surplus volume of the burnt gases may escape freely at the rear, through the open end; thus, the influence of compressing the un-

2

burnt part of the mixture by the burnt gases is non-existent. The velocity of displacement of flame front, so defined, is the specific velocity of flame propagation.

5 This specific velocity of flame propagation depends on three main features:

- (1) Chemical composition of a mixture, i. e. kind of fuel and air excess coefficient;
- (2) Degree of homogeneity of the air-fuel mixture, i. e. degree of mixing;
- (3) Initial physical conditions, i. e. pressure and temperature of the unburnt mixture.

The specific velocity of flame propagation is actually very low, e. g. in a chemically correct air-gasoline mixture and in standard atmospheric pressure-temperature conditions, it is of the order of 4 feet per second. If in the same conditions the kind of fuel changes, the specific velocity of flame propagation changes also within certain limits, being for instance a little higher for ethyl alcohol, considerably higher for hydrogen, etc.

15 The specific velocity of combustion depends solely on the probability of the meeting between molecules of vaporised fuel with an adequate number of oxygen molecules. If, therefore, the mixture is homogenous and supposedly at rest, the phenomenon is conditioned only by the mean distance between the molecules which have to meet on the one hand, and by the mean molecular velocity on the other. In other words, the only physical parameters influencing the phenomenon are pressure and temperature of the unburnt mixture, according to the kinetic theory of gases.

20 30 35 The air excess coefficient influences considerably the specific velocity of combustion. The maximum of this velocity occurs in a mixture a little richer than chemically correct, while it drops very quickly when the air excess coefficient increases or decreases, e. g. for 50 per cent air excess, this velocity is only 40 per cent of that for a chemically correct mixture. This must be so, as in both cases the mean distance between the molecules having to meet increases.

40 45 50 55 This mean distance increases also when the mixture is not homogeneous, all other conditions remaining the same. The degree of homogeneity is, therefore, very important for attaining the possible maximum of velocity of flame propagation, and any means to attain the high degree of homogeneity in an actual combustor are desirable, provided this does not cause too great losses of energy (e. g. loss in pressure in a duct). One of such means is a vortex created artificially

in a flow, either before or during combustion. But even an ideal homogeneity of the mixture will only permit the attaining of the value of specific velocity of combustion as theoretically expected in an ideal case, this value being very low. No vortex can permit us to exceed this velocity in actual practice, as such a vortex may be only of the order of a few hundred feet per sec. while the mean molecular velocity is of the order of a few, and maybe several thousand feet per sec.; thus, the resultant velocity vector remains practically unaffected, the same holding true for the probability of meeting of molecules.

The only adequate solutions seem to be: (1) considerable lowering of the velocity of flow of mixture; (2) considerable shortening of the distance to be run over by a flame.

The first solution is in common use. However, it increases considerably the bulk and weight of any combustor—all the more, because a properly designed diffuser must be applied to lower the flow velocity with a minimum of loss in dynamic head.

In order to explain the other solution, consider a tube of constant cross-section in which air-fuel mixture is flowing with a velocity of, say, 160 ft./sec. The mixture is ignited at a certain point lying on the tube axis. According to the theoretical principles, in a mixture at rest the flame is propagated at a constant velocity in all directions along straight lines starting from the point of ignition, the surface of the flame being spherical. This propagation remains the same if the whole mass of mixture is in motion with a certain constant velocity, in our case 160 ft./sec.; but here the flame velocity must be regarded as relative to the mass of mixture supposed to be at rest. The flame is, therefore, drawn by the flow velocity.

The combustion is not ended until the flame reaches the tube wall, i. e. it must cover a distance equalling the tube radius. Let the tube diameter be 6 inches; thus, the necessary lapse of time will be $\frac{1}{8}$ sec., provided the specific velocity of combustion is 2 ft./sec. During the same lapse of time the flame would be drawn by the flow velocity along the tube to a distance of 10 feet if the flow velocity were constant; in fact this velocity must increase with the temperature and the figure of 10 feet per sec. is practically greater. Thus, in order to accomplish combustion inside the tube, its length must be at least twenty times its diameter.

The principle of my invention is as follows:

In order to shorten a distance to be traversed by a flame in the combustor, flames are caused to issue at a plurality of points which are distributed equidistantly over the cross-section of the tube. This is done by a burning gas brought to the flame distribution points from a special small burner, in which only a low percentage of the whole heat output is released. This auxiliary burner may be of any kind, for instance of a kind in which the flow velocity is only considerably lowered; actually, this does not affect the weight and bulk of the whole combustor, as it is a question of a small auxiliary device.

A further feature of my invention is a device whose aim is to secure a very homogeneous air-fuel mixture. For this reason the fuel is previously vaporised, before mixing with air, in a vaporiser, this latter receiving a small part of the heat contained in the whole mass of gases, during or just after combustion. The vaporized gas is led to a distributor which is similar to the device which distributes the ignition flame, but is

10
15
5

located in the duct upstream of the ignition flame distributing device. The vaporised fuel enters in contact with the air in many points, distributed equidistantly over the tube cross-section, thus enabling the air-fuel mixture to become very homogeneous.

Vaporisation of fuel not only facilitates in rendering the mixture homogeneous, but also precludes all possibility of icing during fuel spray.

The construction of my combustor is as shown in the accompanying drawing, in which:

Figures 1 and 2 represent respectively vertical and horizontal longitudinal sectional views, as obtained in cutting by two planes perpendicular to each other and passing through the axis of symmetry.

Fig. 3 is a perspective view, partly broken, of one of tubes 6 and 18 as appearing in Figures 1 and 2.

Fig. 4 is half of a sectional view showing another kind of auxiliary burner, different from that shown in Fig. 1.

Fuel comes from fuel tank 1, through tube 2, under desirable pressure, to the vaporiser 3. It next passes, in the form of vapor, through tube 4 to the fuel distributor and mixer 5'. Here the fuel gas passes from the annular chamber to the set of parallel small tubes 6, whose cross-section is in the form of airfoil, in order to reduce the drag. These tubes are distributed equidistantly over the cross-section of the main air duct 7, air entering at 8 in the direction of the arrow. One of the tubes 6 is shown in larger scale in Fig. 3. Along the trailing edge of every such tube a set of equidistantly distributing incisions 9 is made, the distance between two adjacent incisions equalling that between two adjacent tubes; fuel vapor escapes through these incisions and enters the main air stream.

In order to facilitate the thermal dilatation of tubes 6, they are made of two parts, 10 and 11, one sliding in the other.

A small part of the air output enters the bypass 12; it is compressed in diffuser 13 (this additional compression serving to overcome the aerodynamic resistance in ignition flame distributor 17), while its velocity diminishes considerably. A small part of the fuel vapor passes from distributor 5, through tube 14, to combustion chamber 15 of the auxiliary burner and mixes with air. The mixture is then ignited by spark plug 16. The velocity of stream in 15 is chosen so low as to secure continuous combustion without any artificial means to maintain it, spark plug 16 serving only for starting. Burning gases from the auxiliary burner then pass to the annular ignition flame distributor 17, and next to tubes 18, set similarly to tubes 6 and being of similar shape and construction. Ignition flame distributor 17 is placed at a distance from 5, at which homogeneity of the air-fuel mixture is already attained. Burnt gases leave the combustor at 19.

The kind of source of ignition flame being in principle immaterial, solution of auxiliary burner as described serves only as an example. Another possible solution, simpler in principle, is shown in Fig. 4. Here no auxiliary burner exists, and ignition flame is borrowed from the main flow of burning gases. A small part of the flaming gas escapes through tube 21, whose inlet end 22 is set against the main flow direction. Then these gases pass through diffuser 23, in order to create such increase in pressure as may be necessary to offset the resistance to flow in ignition flame

75

distributor 17 and tube 18. In such a solution, the starting spark plug may be placed either at 24 or at 25.

Tubes 18 are made from tungsten sheets, in order to protect them against high flame temperature. This temperature has to be high in order to certainly exceed the flash point of the mixture. Its value may be controlled by controlling the quantity of fuel vapor entering auxiliary combustion chamber 15, i. e. the air excess coefficient in this auxiliary device. Even a chemically correct mixture may be applied here if necessary, but in this case it is preferable to manufacture all parts of the auxiliary burner from tungsten or, at least, from high quality stainless steel.

Tube 20 serves to feed the auxiliary burner with fuel at the moment of starting.

The distance between tubes 18 is to be chosen according to practical considerations. The shorter this distance, the shorter becomes the length of the main duct 4; but if the number of tubes 18 is too great, the aerodynamic resistance they offer may increase beyond the admissible limit. From this viewpoint, the ratio of profile width 18 and of the distance between two adjacent profiles must be kept as small as possible. It is, therefore, advisable to apply profiles which are sufficiently slender and as small as feasible.

What I claim as my invention is:

1. A combustor for high-flow velocities of the type described, comprising a duct of circular cross-section, said duct being open at one end to receive air and at the opposite end to discharge the products of combustion; a fuel tank; a vaporizer mounted in heat transferring relationship with said duct; two annular chambers concentrically mounted upon said duct; a plurality of open-ended tubes of airfoil cross-section parallelly disposed and mounted in the wall of the duct in the region of each annular chamber, the open ends of the tubes entering the annular chamber associated therewith; a plurality of perforations in the trailing edge of each of the said tubes of airfoil cross-section; means for delivering fuel from said tank to said vaporizer; means

for delivering vaporized fuel from the vaporizer to one of said annular chambers, and thence to the tubes associated therewith, the perforations in said tubes constituting means whereby fuel may escape from the tubes and mix with air entering the open inlet end of the duct; ignition means; and means for leading a relatively small quantity of vaporized fuel mixed with air past said ignition means; means for delivering the burning mixture produced by ignition of the fuel led past the ignition means, to the other annular chamber, and the tubes associated therewith, whereby the said burning mixture enters the duct through the perforations in said tubes at a plurality of points; the perforations in each member of each series of tubes being equidistant from one another, and the tubes being spaced apart from one another a distance equal to the distance between an adjacent pair of perforations in one of the tubes, so that the said burning mixture enters the duct at a plurality of points equidistantly spaced over the cross-section of the duct.

2. A combustor as defined in claim 1, in which the tubes of airfoil cross-section are each made up of two parts, one part being telescopically receivable within the other to accommodate thermal dilatation of the combustor.

3. A combustor as defined in claim 1, in which the means for delivering the said burning mixture to the said other annular chamber includes a diffuser having a cross-section which increases with proximity to the said other annular chamber.
